Charles H. Sanborn
by James R. Hodder
Attorney

UNITED STATES PATENT OFFICE

CHARLES H. SANBORN, OF NEWBURYPORT, MASSACHUSETTS, ASSIGNOR TO HALEY, CATE, ROCKWOOD COMPANY, INC., OF EVERETT, MASSACHUSETTS, A CORPORATION OF MASSACHUSETTS

YIELDING ATTACHMENT FOR SEWING MACHINES

Application filed August 30, 1930. Serial No. 478,920.

My present invention is an attachment for sewing machines, and is an improvement on the machine and device of my prior invention shown in my patent application Serial No. 467,691, filed July 14, 1930. In my said prior application I illustrated, described and claimed an improved attachment for sewing machines which would enable two layers or edges of material, such as in shoe leather or glove manufacture, or the like, to be attached by a single row of stitching with a beading or piping interposed therebetween simultaneously with the stitching, and providing for all three articles to be thus united at a single operation simultaneously and by a single row of stitching.

My said prior device was satisfactory in operating upon two layers which were the two layers to be joined with the interposed beading when all three were of single sheets or of substantially uniform thickness but was not satisfactory where either of the layers to be united included a seamed or sewed joint owing to the inequalities in thickness in the particular layer having such a seam over which the piping and the other layer had to be joined.

My present invention provides means to automatically take care of any such inequalities in the layers or parts to be sewed and attached, such as often occur in shoe manufacture where the piping is to be attached over a previously joined or stitched portion.

In carrying out my present invention I utilize an attachment for sewing machines substantially similar to that of my prior device but having yielding means for guiding the piping so that during the feeding operation the stitching, guiding and feeding of the beading will be continuously carried out irrespective of inequalities in either of the layers.

Referring to the attached drawing showing a preferred embodiment of my invention,

Fig. 1 is a side view of the yielding device in combination with a presser foot and adjacent parts of a sewing machine, shown in fragmentary form;

Fig. 2 is an end view;

Fig. 3 is a plan view illustrating the feeding of the two layers and the interposed beading over a seamed portion in one layer;

Fig. 4 is a cross-sectional view on the line 4—4 of Fig. 3;

Fig. 5 is a cross-sectional view on the line 5—5 of Fig. 3;

Fig. 6 is a fragmentary view of the beading guide and edge guide;

Fig. 7 is a plan view of a shoe upper comprising a vamp, quarters and tongue;

Fig. 8 is an enlarged plan view illustrating uniting the vamp, beading and tongue portions of the shoe upper shown in Fig. 7, and

Fig. 9 is a cross-sectional view on the line 9—9 of Fig. 8.

As shown in the drawing, a portion of a sewing machine frame is indicated at 1, to which is attached my novel device. 2 indicates the usual needle and 3 the presser foot of the sewing machine.

To a portion of the frame 1 is secured a bracket 5 by attaching screws 6, 6, said bracket having a depending portion 7. Preferably the bracket 5 has large recesses 8, 8, through which the securing screws 6, 6, pass to afford means for vertical adjustment of the entire apparatus. Attached to the portion 7 is a plate 10 secured at its uppermost end by a set screw 11 and secured at the lower portion by a set screw 12 passing through an elongated longitudinal slot 13 to permit lateral adjustment of the plate 10 on the portion 7. These parts 5 and 10 are thus capable of vertical, as well as lateral, adjustment to bring the guide 20 into desired position with relation to the work and the worktable 9.

In my former invention I provided the beading or piping guides substantially rigid with a holding bracket excepting for slight adjustability, and in my present device I provide the beading guide on a pivot, so that same may yield when it strikes a raised portion, such as the seam in one of the layers being united. For this purpose I secure the beading guide itself 20 on the end of a pivoted lever 21 with a portion formed to provide an upper guiding face 22, the slot 23 in the beading guide 20 being of appropriate

width and size to receive the beading or piping being operated on. This lever 21 is pivoted to the lower end of the plate 10 by a set screw 25, and said lever has an upwardly extending arm 26 enlarged at its uppermost end, as best shown in Fig. 2, and having therein a slot 27 to receive the stem of an adjusting screw 30. This screw is threaded into a tapped recess in the depending portion 10 7 of the bracket 5.

A pair of springs 28 and 29 are interposed between the head of the screw 30 and the upper portion 26 of the pivoted lever and the inner surface of said lever and the member 15 7 respectively, as best shown in Fig. 1. Adjustment of the screw 30 controls the tension of these springs 28 and 29, which springs, in turn, hold the pivoted lever 21 yielding in desired position. I may provide 20 washers between the springs 28 and 29, and the portion 26 of the lever, which washers will span the slot 27 and facilitate the rocking of same between the springs and over the shank of the adjusting screw 30 during the 25 yielding action of the guide 20, as it slides over an obstruction, such as the increased thickness afforded by a seamed portion in the work below.

In Figs. 3 and 4 I illustrate the operation 30 of my present improved yielding beading guide when engaged in the operation of uniting interposed piping 33 between a smooth layer 34 and the seamed joint 35 of the bottom layer 36 and 37 in the work.

In Fig. 7 I illustrate a shoe construction 35 wherein the vamp 40, preferably of a single layer, is to be united to the previously joined quarters of the shoe comprising sections 41 and 42 in each side joined by a seam 43 and a 40 tongue 44.

Figs. 8 and 9 are illustrative of this operation 45 wherein the beading guide 20 yields upwardly when going over the length of the seam occasioned by the tongue 44 being united to the portion 41 in the shoe upper materials.

In the operation of the present device the adjustment for height is made on the bracket 5 by the screws 6, 6 through the slotted recesses 8, 8 therein into corresponding tapped recesses in the portion 1 of the sewing machine.

The plate 10 may be adjusted and the set screw tightened to hold it in desired position 55 with the line of feed of the work. The tension screw 30 may be adjusted at any time to provide desired tension on the pivoted lever 21. The beading or piping 33 is then threaded through the recess 23 of the beading 60 guide 20 and the upper and lower layers of the work are positioned and fitted, the upper layer being pressed against the guiding face 22, thereupon the feeding of the machine operates as a normal sewing machine, feeding 65 the work forwardly, with the beading guide

20 having capacity to yield and ride over and upon, and then down after any increased thickness in the work is interposed in the path of the line of stitching.

It will be thus appreciated that I have 70 devised an automatic yielding piping guide which automatically facilitates the operation of the machine of my said prior application and which will compensate for any uneven thickness in the layers presented by a seamed joint, edge, or section, such as may be offered by seams 43 or by substantial length, as illustrated at the junction of the tongue 44 with the adjacent portions.

What I claim is:

1. An attachment for sewing machines including sewing instrumentalities, comprising a support fixed to said machine, a lever pivoted adjacent to the lower end of said support, a tubular guide at one end of said lever and adapted to be positioned between two layers to be united by the sewing instrumentalities and to guide a third layer therebetween, and resilient means on the opposite end of said pivoted lever permitting said tubular guide to automatically yield on meeting increased thicknesses in either the upper or lower layers operated on by the sewing instrumentalities.

2. An attachment for sewing machines including sewing instrumentalities, comprising a support fixed to said machine, a lever pivoted adjacent to the lower end of said support, a slanting tubular guide at one end of said lever and adapted to be positioned between two layers to be united by the sewing instrumentalities and to guide a third layer therebetween, and adjustable resilient means on the opposite end of said pivoted lever permitting said tubular guide to automatically yield on meeting increased thicknesses in either the upper or lower layers operated on by the sewing instrumentalities.

3. An attachment for sewing machines including sewing instrumentalities, comprising a support fixed to said machine, a pivoted lever adjacent to the lower end of said support, a flattened portion at one end of said lever having a tubular guide therethrough, said flattened portion and said tubular guide being slanting, said flattened portion being adapted to be positioned between two layers to be united by the sewing instrumentalities and to guide a third layer therebetween, and resilient means on the opposite end of said pivoted lever permitting said tubular guide to automatically yield on meeting increased thicknesses in either the upper or lower layers operated on by the sewing instrumentalities.

4. An attachment for sewing machines including sewing instrumentalities, comprising a support fixed to said machine, a pivoted lever adjacent to the lower end of said support, a flattened offset portion at one end of said lever having a tubular guide therethrough,

said flattened portion and said tubular guide being slanting, said flattened portion being adapted to be positioned between two layers to be united by the sewing instrumentalities 5 and to guide a third layer therebetween, and resilient means on the opposite end of said pivoted lever permitting said tubular guide to automatically yield on meeting increased thicknesses in either the upper or lower layers 10 operated on by the sewing instrumentalities.

5. An attachment for sewing machines including sewing instrumentalities, comprising a support fixed to said machine, a lever pivoted adjacent to the lower end of said support, a flattened portion at one end of said lever having a tubular guide therethrough, said flattened portion and said tubular guide being positioned angularly, said tubular guide slanting from its entrance to its outlet, 15 said flattened portion being adapted to be positioned between two layers to be united by the sewing instrumentalities and to guide a third layer therebetween, and resilient means on the opposite end of said pivoted lever permitting said tubular guide to automatically yield on meeting increased thicknesses in either the upper or lower layers 20 operated on by the sewing instrumentalities.

6. An attachment for sewing machines including sewing instrumentalities, comprising a support fixed to said machine, a lever pivoted adjacent to the lower end of said support, a flattened portion at one end of said lever having a tubular guide therethrough 35 and adapted to be positioned between two layers to be united by the sewing instrumentalities and to guide a third layer therebetween, the opposite end of said lever projecting upwardly adjacent to said support 40 and having an elongated slot therein, an adjusting screw extending through said elongated slot and into said support, and resilient means associated with the slotted end of said lever permitting said tubular guide portion 45 to automatically yield on meeting increased thicknesses in either the upper or lower layers operated on by the sewing instrumentalities.

7. An attachment for sewing machines including sewing instrumentalities, comprising 50 a pivoted lever, a tubular guide at one end of said lever adapted to be positioned between two layers to be united by the sewing instrumentalities and to guide a third layer therebetween, and resilient means associated 55 with the opposite end of said pivoted lever permitting said tubular guide to automatically yield on meeting increased thicknesses in either the upper or lower layers operated on by the sewing instrumentalities.

8. An attachment for sewing machines including sewing instrumentalities, comprising a pivoted lever, a tubular guide at one end of said lever adapted to be positioned between 60 two layers to be united by the sewing instrumentalities and to guide a third layer there-

between, said tubular guide slanting from its entrance to its outlet, and resilient means associated with the opposite end of said pivoted lever permitting said tubular guide to automatically yield on meeting increased 70 thicknesses in either the upper or lower layers operated on by the sewing instrumentalities.

In testimony whereof, I have signed my name to this specification.
